JOHN DOPYERA, OF LOS ANGELES, CALIFORNIA, ASSIGNOR TO GEORGE D. BEAUCHAMP,
T. E. KLEINMEYER, AND PAUL BARTH, OF LOS ANGELES, CALIFORNIA

STRINGED MUSICAL INSTRUMENT

Application filed October 12, 1926, Serial No. 141,115. Renewed October 22, 1929.

This invention relates in general to musical instruments and more particularly to stringed musical instruments, such as guitars, banjos and the like. The main object 5 is to provide a stringed instrument in which instead of the usual membrane or skin, I have provided one or more thin sheet metal resonators, preferably of aluminum, on which the bridge supporting the strings 10 of the instrument is mounted. Thus the vibrations set up in the strings of the instrument when the same is being played can be transferred to the one or more resonators and amplified substantially, for providing 15 a louder tone and more resonant qualities than can ordinarily be provided by the employment of the usual membrane or skin.

Other and minor objects of invention will appear as the description progresses.

20 In the accompanying drawing I have shown a preferred embodiment of my invention, subject to modification within the scope of the appended claims without departing from the spirit thereof. In the 25 drawing:

Fig. 1 is a plan view of the body of an instrument such as a steel guitar with the cover omitted, showing a form of my invention embodying four resonators.

30 Fig. 2 is a similar view of an instrument embodying five resonators.

Fig. 3 is a fragmentary section of one of the resonators showing a method of supporting the bridge thereon.

35 Fig. 4 is a top plan view of an instrument of the character shown in Fig. 1 with a cover attached thereto.

Fig. 5 is a transverse section of the assembled instrument on line 5-5 of Fig. 1.

40 Fig. 6 is a transverse section of the same on 6-6 of Fig. 1.

It will be understood in the consideration of this invention that while I have shown an arrangement of resonators and a 45 structure embodying three, four and five of such resonators, that I may vary the number and change the form of the body of the instrument as the number of resonators are varied. For instance an instrument of the 50 ukulele or banjo ukulele type may be con-

structed in accordance with my invention, in which case but a single resonator is employed for supporting the bridge on which the strings are held in tension.

Likewise it will be understood that the 55 resonance of the instrument embodying my invention will be influenced by the number, size and area of the resonators embodied in the instrument; also different kinds of metals may be employed in the manufacture of the resonators; all of these points being immaterial to my invention.

Now, referring to said drawings, my instrument has the usual body B with a neck N, but in lieu of the usual membrane or 55 skin stretched over the body B, I provide a cover of thin sheet metal as at C, suitably attached to the upper edge of the body B by means of screws as at 1, 1 etc., or otherwise. The bottom of the body B is covered 60 preferably by a wooden member b attached by means of screws 2, 2 etc. or otherwise, to the lower edge of the body B.

Internally of the body I provided a central partition 3 which subdivides the interior of the body into two compartments 4 and 5 adjacent to the cover C and the bottom b, respectively. The partition 3 is suitably secured to the body B and is mounted on the upper edge of a band as at 65 70 75 80 85 90 95 100 6 6, either formed internally of the member b or formed separate and attached thereto by suitable means.

The partition 3 has a plurality of circular openings as at O, O etc. which are concentrically arranged around a smaller central opening 7 in said partition. Each of the openings O is covered on the upper side of the partition 3 by means of a concically formed resonator R, which is provided with an annular bead 8. Externally of the beads 8 the edge portions of the resonators overlie the openings O and rest upon the upper side of the partition 3. Said edge portions are clamped to the partition 3 by means of annular retaining members r which are secured to the partition 3 by means of screws 9, 9 etc.

The bridge A which supports the strings 10, 10 etc., of the instrument is loosely sup-

ported on a spider S which may be integrally formed or of composite character and provided preferably with a central annular portion 11 concentric with the opening 7 in the partition 3 and having radially formed arms α , α etc. extended outwardly from the portion 11 to and overlying the centers of the resonators R, R etc. as shown in Fig. 3.

10 Each of the arms α of said spider S has a flat foot 12 formed thereon which is indented at 13 on the lower side with a drill or tool so as to receive the conically formed end 14 of a screw 15 which is centrally positioned in each of the resonators and is extended therethrough and held thereon by means of a nut 16. The bridge A is additionally supported on a single resonator R' which is mounted in the compartment 5 of the body 20 and on the upper side of the bottom b. The resonator R' is attached to and supported on the bottom b by means of rings r' as in the case of the resonators R, and the same is connected with the bridge A by means of a 25 metallic spring member D which is formed by bending the member a plurality of times in reverse directions for providing resiliency. Said member terminates in portions 17 and 18 which are, respectively, held in contact 30 with the resonator R' and the bridge A as shown in Fig. 5.

The member D extends through the central opening 7 of partition 3 and it will be observed that the bridge A which supports 35 the strings 10 in tension, is mounted on the spider α and on the central member D, and the vibrations set up in the strings 10 of the instrument will be communicated through the bridge A and the spider S and member 40 D to the resonator R, R etc. and the resonator R'.

For convenience in playing the instrument, especially in the case of a steel guitar embodying my improvements, I provide an 45 arched rest 20 formed of metal and overlying the bridge A and strings 10, as shown in Fig. 5, said member 20 has feet 21, 21 at the ends, which are attached by means of screws or rivets 22 to the cover C. The member 20 50 thus serves as a rest for the arm or hand when the instrument is being played.

An opening 23 provided in the cover C in which the bridge A is positioned and other openings 24, 24 are provided therein 55 as in the case of violins and other types of instruments, by means of which the tones set up by the vibrations of the resonators within the body may be rendered more audible than would otherwise be possible.

60 In certain types of instruments I may provide on the bottom b an amplifier in the form of a horn as at H in Fig. 5, suitably attached to the member b and beneath the resonator R', by means of which the vibrations and 65 tones of the instrument may be substantially

amplified when the instrument is played before audiences in theaters or in large halls. Also by a slight rearrangement of the resonators, the resonators R, R may likewise be provided with horns or amplifier as indicated 70 in Fig. 6 in broken lines. As in other types of instruments the strings 10 are connected to a tail piece as at T, formed of metal and suitably attached to the rear end of the body B and the other ends of the strings are connected with pegs whereby the strings may be tightened for tuning. 75

In attaching the resonators R to the partition 3 and the resonator R' to the bottom b, the same may be spaced from said members by strips of felt, rubber or other material such as cork, for insulating the same from the members on which they are supported in order that maximum tonal qualities may be provided. 80

I have found that resonators made of aluminum so thin that the metal may be readily indented by pressure of the fingers, have peculiar resonant qualities which are not possessed by other metals, or by any 85 metal of like thickness.

I have also discovered that the provision of the annular beads 8 of angular cross section near the margins of the resonators substantially amplify the vibrations set up in 90 the resonators. This is due to the fact that the edges of the resonators are tightly held and the beads 8 provide readily yieldable annular portions intermediate the margins and the cones which permit of a maximum resiliency of the cones and render the resonators more delicate and sensitive to the vibrations set up therein. 95

Experiments have also determined that the best results can be obtained by using three 100 of the resonators. The use of less than three resonators substantially decreases, and the use of four slightly decreases the volume. In some cases, four resonators may be used with good results, but it is preferable to use 110 three and never less than three. 105

What I claim is:

1. A stringed musical instrument including a hollow body, a top having an opening therein, a plurality of strings held in tension over said body, a metallic tensioning member positioned centrally within the body, a bridge supported by said tensioning member, and positioned adjacent said opening, a plurality of metallic resonators positioned within the body and concentrically arranged with respect to said tension member, and a member having arms engaging central portions of said resonators and a central portion engaging said bridge, for the purpose described. 115

2. A stringed musical instrument including a body having top and bottom portions spaced apart, a partition therebetween provided with a plurality of concentrically ar- 120 125

ranged openings, a centrally formed opening being provided in said top, a plurality of metallic resonators of conical cross section mounted on said partition over said concentrically arranged openings, strings held in tension over said top, a metallic spider, a bridge on said spider adjacent the opening in said top, said spider having portions contacting with central portions of each of said resonators for communicating the vibrations set up in said strings to said resonators.

3. A stringed musical instrument comprising a body, a plurality of metallic resonators of conical cross section supported therein at their edges and having annular corrugations formed near the supporting edges thereof for imparting maximum vibrational qualities thereto, strings stretched over said body, a spider, and a bridge on said spider in direct contact with said strings, said spider connecting with the apices of said resonators for communicating the vibrations set up in the strings to the resonators.

4. A stringed musical instrument comprising a hollow body having strings held in tension thereon, a plurality of metallic resonators of conical cross section and mounted within said body, said resonators having annular flat attaching portions and annular beads of angular cross section formed near the attaching portions, and a spider common to and engaging the apices of all of the resonators, a bridge on said spider engaging said strings for communicating the vibrations from the strings to the resonators.

5. A stringed musical instrument comprising a body having spaced top and bottom portions, a partition in said body intermediate the top and bottom portions, said top and said partition having openings therein, a plurality of conical metallic resonators mounted on said partition within said body and overlying the openings in said partition, said resonators having marginal attaching portions and annular corrugations formed near the attaching portions, a plurality of strings held in tension over the top of said body, and a spider having portions connected with the apices of said resonators and a bridge on said spider engaging said strings for the purpose described.

6. A stringed musical instrument comprising a hollow body having an opening in the top, strings held in tension over said top, a plurality of metallic resonators supported at their margin within said body and a spider having a plurality of arms connected with the central portions of said resonators, a bridge on said spider disposed adjacent the opening in said top and engaging said strings as described.

JOHN DOPYERA.
